United States Patent Office.

ADOLPH F. BALLAS, OF POTTSTOWN, PENNSYLVANIA.

Letters Patent No. 76,978, dated April 21, 1868.

IMPROVED RAILWAY-SWITCH.

The Schedule referred to in these Letters Patent and making part of the same.

TO ALL WHOM IT MAY CONCERN:

Be it known that I, ADOLPH F. BALLAS, of Pottstown, in the county of Montgomery, and State of Pennsylvania, have invented new and useful Improvements in Railroad-Switches; and I do hereby declare that the following is a full, clear, and exact description thereof, which will enable others skilled in the art to make and use the same, reference being had to the accompanying drawings, and to the letters of reference marked thereon.

Figure 1, Sheet I, is a plan or top view of a section of a railway, showing my improved switch applied thereto.

Figure 2, Sheet I, is a longitudinal section between the switch-rails.

Figure 3, Sheet I, is a transverse vertical section through the line xx , fig. 1, in front of the end of the switch-rails.

Figure 4, Sheet I, is a transverse vertical section through the line yy , fig. 2, showing the point of connection between the tread of the switch-rail and the main track.

Figure 5, Sheet I, is a transverse vertical section through the line zz , fig. 2, showing the construction of the switch-rail at that point, and the full tread of the same.

Figure 6, Sheet II, is an end elevation of the switch-stand and target, showing the gearing for operating the latter.

Figure 7, Sheet II, is a vertical section between the plates upon the switch-stand in the line ww , fig. 1.

The many accidents which occur through the switches now in use have led to the invention by me of a switch, that, in itself, will be sufficient to guard against accidents, however careless or neglectful the switchman may be; and by the present invention such a switch is obtained. The principle of the switch consists in arranging it in such a manner as to be self-acting through a counter-weight suitably applied thereto.

A, in the drawings, represents the main track, and B the connecting branch or side track, between which and the main track connection is had, when so desired, by the switch-rails C.

These rails C are connected together by cross-rods D, and attached to the chains E of the rails in the ordinary manner, so as to be properly operated or brought into the positions desired.

These switch-rails are so set as to effect an unbroken and constant connection of the side and main tracks; that is, the switch being in this position, trains or cars pass in the direction of the arrow, both on the side track and main track, but a train or cars passing in the opposite direction thereto will run into the side branch.

The switch-rails or tongues C are hung upon pivots at α , and held in position through the connecting-rods, as above stated, by the counter-weight F.

The improvements of the tongues C, over those heretofore in use, consist—

First, that the rails against which they set need not be notched, but can be preserved complete, thus avoiding the shock which a passing train always receives from an injured rail.

Second, that the tongue is much stronger than generally, always giving a full bearing to the head of the wheel, until it transfers the load to the rail, where the point of the tongue fits closely between the head and foot of the L-rail.

In all switch-tongues heretofore constructed, the end of the tongue was made wedge-shape and adapted to fit into a notch in the side of the rail. The end of the tongue was of the same height as the rail, and presented a very thin or narrow edge to the tread of the wheel, and was therefore liable to be crushed and destroyed by heavily-laden trains, while the notches in the rails to receive the ends of the tongues weakened said rails in a great degree. The point of the tongue was not only obliged to sustain the entire load of the passing train, but was liable to displacement by the concussion of the flanges of the wheels. My invention is designed to avoid these objections. The end of the tongue is constructed lower than the rail, and is adapted to fit snugly against the web and the under side of the tread, avoiding the necessity of forming notches in the latter.

By these means the tongue has no weight to carry at its weakest place, and suffers no concussion, but merely has to resist the side pressure of the flange to the wheel, thus lasting a much longer time than any other.

form of tongue hitherto employed, and which have to bear the full weight of the passing load on the weakest place.

The flange of a train running in the direction of the arrow, with the switch set as indicated in the drawings, will be driven between the movable tongue and the stationary rail, and, acting like a wedge, press the tongue out, raising the switch-weight F, the connection between which will be hereinafter described; thus making a continuous track, and allowing the train to pass without the least danger of being thrown off the track. After the train has passed, the counter weight will press the tongue against the rail, and the switch will be in its former position.

The weight F is applied to one end of a rod, H, that at its inner end is hung so as to turn upon a centre, between two plates I, hung to the switch-stand J, so as to swing thereon, and at one end connected, through a rod, K, with the switch-rails or tongues C.

Between these plates I are stop-blocks M, for the weight-arm H to rest upon.

When the weight is in the position shown in fig. 7, the switch will effect an unbroken connection of the main track, so that trains can run in both directions of it, and in coming from the side track, in the direction of the arrow, the train will gain the main track by means of the sliding tongues, without the necessity of turning the switch; and when the weight is in the position shown in dotted lines of the same figure, it will gain the side track.

In either position of the counter-weight, the target P, that is suitably connected therewith through pinion-wheels O, will revolve, and shows a white or other surface, as may be arranged or agreed upon, and thus indicate to the engineer of the train how the switch is set.

Having thus described my invention, I claim as new, and desire to secure by Letters Patent—

1. The switch-tongues, constructed as described, with their points lower than the tread of the rails A, B, and adapted to fit against the web, and below the tread of said rails, free from contact with the tread of the car-wheels, as herein described, for the purpose specified.
2. In combination with the above, I claim the counter-weight, constructed and arranged to operate as herein described, for the purpose specified.
3. In combination with the tongues C and counter-weight F, the revolving target P and gearing O, operating substantially as described, for the purpose specified.

ADOLPH F. BALLAS.
